UNITED STATES PATENT OFFICE.

FRANKLIN D. CORNELL, OF ADRIAN, MICHIGAN, ASSIGNOR OF FIVE-EIGHTHS TO MILLARD F. LYON, ALICE A. AGNEW, AND ISAAC L. WILCOX, OF SAME PLACE.

PENCIL-SHARPENER.

SPECIFICATION forming part of Letters Patent No. 594,839, dated November 30, 1897.

Application filed May 1, 1896. Serial No. 589,826. (No model.)

To all whom it may concern:

Be it known that I, FRANKLIN D. CORNELL, a citizen of the United States, residing at Adrian, in the county of Lenawee, State of Michigan, have invented certain new and useful Improvements in Pencil-Sharpener; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in pencil-sharpener; and it consists in the construction and arrangement of parts hereinafter fully set forth, and pointed out particularly in the claims.

20 The object of the invention is to provide simple and effective means in connection with a chuck pencil-sharpener, whereby the pencil may be readily sharpened and the danger of breaking the lead or marking material obviated, at the same time providing for a receptacle to retain the shavings cut from the end of the pencil, which object is attained by the device illustrated in the accompanying drawings, in which—

30 Figure 1 is a view of my improved sharpener mounted on a table, portions being broken away to more clearly show construction of parts. Fig. 2 is a vertical transverse section on line 2 2, Fig. 1. Fig. 3 is a perspective of the hollow mandrel carrying the knife for sharpening the wooden case as well as the supplementary socket-chuck carrying the cutter-head for pointing the graphite or marking substance running through the 35 wooden case of the pencil. Fig. 4 is an enlarged end elevation of the auxiliary or graphite-pointing cutter-head seated in its retaining-chuck. Fig. 5 is a perspective of the detachable head carrying the cutting-bit.

40 Referring to the letters of reference, A designates a clamping-bracket of suitable form, having a thumb-screw *a* for securing said bracket to a table or suitable support. Journaled in said bracket is a shaft *B*, having 45 suitable bearings *b* and provided with a crank

B'. On the inner end of said shaft is a suitable cylindrical socket *C*, which rotates with said shaft and detachably receives the knife-carrying mandrel and pointing cutter-head in the open outer end thereof. Said socket 55 *C* is provided in one side with an opening *c* opposite the cutting-knives of the mandrel and head to allow for the escape of the chips. Surrounding said socket is a cylindrical case *C'*, which is adapted to receive and hold the 60 chips or shavings from the pencils, said case having an opening therein closed by the slide *d*, which affords means for emptying the chips or shavings therefrom when it shall have become filled.

65 *D* designates the removable hollow mandrel for pointing the wooden casing of the graphite or marking substance. This mandrel is generally cylindrical in form, but is provided with a tapering aperture running 70 longitudinally thereof which converges inward from the mouth-opening *D'*. Formed in the side of said mandrel *D* and extending longitudinally thereof is an inclined opening *e*, which communicates with the tapered aperture therein and in which a knife *f* is secured whose edge projects into the tapered aperture of the mandrel and stands on a plane with the wall thereof. Projecting from the outer face of the mandrel *D* is a lug *h*, which 75 is adapted to enter a way *i*, formed in the inner wall of the socket *C*, as shown in Fig. 1, to retain said mandrel in place when inserted in said socket and cause it to rotate therewith when said socket is rotated through the 80 medium of the shaft *B* and crank *B'*.

85 *E* designates an auxiliary collar or socket chuck in which is mounted a supplementary cutter-head *F*, which is secured therein by a set-screw *e'*. The head *F* is provided with a 90 tapered aperture and a lateral opening communicating therewith, in which is located an inclined knife *h'*, which projects slightly into said aperture parallel to the line of its tapered wall. This chuck *E* is independent of 95 the mandrel *D*, but is attached thereto by flexible arms *k*, on opposite sides thereof, which cause the chuck *E* to rotate with said mandrel, but permit of lateral vibration of said chuck.

100

In the operation of this device the hollow knife-carrying mandrel D, with its accompanying chuck E and complementary cutting-head F, is placed in the socket C, as shown in Fig. 1. The pencil to be sharpened is inserted in the aperture D' of the mandrel D, when by a rotation of the shaft B, through the medium of the crank, said mandrel is revolved, causing the knife f to cut the wood to from the end of said pencil to an acuminate point, the pencil being held from rotating and forced gradually inward as its point is cut away by the rotation of said knife. The position of said knife is such that it only engages the casing of wood around the core of graphite or marking substance in the pencil, the point of which passes untouched through the mandrel D and into the head F, which is flexibly connected with said mandrel D. The knife h' in said head F serves to point the end of the graphite or marking substance forming the core of the pencil; and because of the flexible connection between the head F, carrying the pointing-knife, and the hollow mandrel D a lateral movement of the pencil will not result in breaking off the point of the marking material, which is entered in the head F, for the reason that any change in the angle of the pencil is accommodated by reason of the flexible mounting of said chuck E, carrying the head F, so that a long and perfect point may be placed upon the pencil without danger of breaking the point of the marking substance, which is at the same time pointed, as required, through the action of the knife h', or, if desired, the marking substance may be left unpointed by removing the knife in the head F from contact therewith.

It will now be understood that by means of this improved device a pencil or marking-stick of any character may be sharpened and pointed as desired without liability of breaking the point, enabling as well this operation of sharpening and pointing to be perfectly and quickly done, obviating, too, the dirt and litter incident to such work by confining the chips or shavings within the circular case C', from which they may be removed at pleasure.

While I have shown the spring-arms for connecting the auxiliary chuck with the mandrel D, it is evident that any suitable flexible mounting of the auxiliary chuck so as to

cause it to move in unison with the mandrel D, 55 but afford an independent lateral movement thereof, may be employed without departing from the spirit of my invention.

Having thus fully set forth my invention, what I claim as new, and desire to secure by Letters Patent, is—

1. In a pencil-sharpener, the combination of the mandrel or socket for receiving the pointed end of the pencil, the flexibly-mounted rotary chuck adjacent thereto carrying a 65 knife for pointing the end of the marking substance.

2. In a pencil-sharpener, the combination of the rotary mandrel for pointing the wooden casing of the pencil, the auxiliary chuck rotating therewith and flexibly connected thereto so as to have independent lateral movement, said chuck carrying a pointing-knife. 70

3. In a pencil-sharpener, the combination with the rotary mandrel for pointing the 75 wooden casing of the pencil, the auxiliary chuck carrying a knife for pointing the end of the marking substance located adjacent thereto, and the spring-arm connecting said chuck and mandrel so as to cause them to rotate in unison. 80

4. In a pencil-sharpener, the combination of the rotary mandrel for pointing the wooden casing of the pencil, the chuck adjacent to the inner end thereof, the spring-arms connecting said chuck with said rotary mandrel, and the auxiliary cutter-head mounted in said spring-supported chuck. 85

5. In a pencil-sharpener, the combination of the adjacent rotary cutting-mandrel and 90 the rotary cutter-carrying chuck, one of which is capable of independent lateral movement.

6. In a pencil-sharpener, the combination of the rotary socket, the wood-cutting mandrel and the flexibly-mounted knife-carrying 95 chuck located in said socket, and means for rotating said socket.

7. In a pencil-sharpener, the combination of the wood-cutting mandrel, the flexibly-mounted cutter-carrying chuck adjacent thereto, and the closed case embracing said parts. 100

In testimony whereof I affix my signature in presence of two witnesses.

FRANKLIN D. CORNELL.
